DISTILLATION OF TAR

Original Filed Dec. 28, 1929

UNITED STATES PATENT OFFICE

STUART PARMELEE MILLER, OF ENGLEWOOD, NEW JERSEY, ASSIGNOR TO THE BARRETT COMPANY, OF NEW YORK, N. Y., A CORPORATION OF NEW JERSEY

DISTILLATION OF TAR

Application filed December 28, 1929, Serial No. 417,195. Renewed September 19, 1932.

This invention relates to an improved process of distilling tar with superheated steam.

Many proposals have been made to distill 5 coal tar with steam, and even with superheated steam, usually by introducing the steam into a body of the tar to be distilled, or by passing the tar and steam countercurrent to each other through a scrubber or 10 tower.

The present invention provides an improved method of distilling tar with superheated steam in which the steam employed has a radically higher temperature than that 15 heretofore proposed for such distillation, and in which such highly superheated steam is employed in a particularly advantageous manner.

The superheated steam which is employed 20 in the present process is superheated to a temperature above that at which complete distillation and carbonization of the pitch residue would take place, and this highly superheated steam is employed so that ob- 25 jectionable carbonization is avoided and rapid and effective distillation accomplished.

The superheated steam which I employ in 20 the present process is superheated to a high temperature, e. g. to a temperature around 500 to 1000° C. Coal tar, if heated to such 30 temperatures, would rapidly carbonize. In the process of the present invention, I overcome such objections to steam of such high 35 temperatures, and I use it in a particularly advantageous manner.

According to the present invention, the 40 highly superheated steam is brought into a chamber containing a body of the tar or pitch to be distilled, and this tar or pitch is atom- 45 ized or sprayed into the steam with such intensity of spray that the steam is almost instantly cooled from its high temperature to a temperature approaching that of the pitch formed while the tar or pitch is rapidly dis- 50 tillied and heated to a temperature approaching that to which the steam is cooled. Such intense spraying or atomizing of the tar or pitch can readily be accomplished by means of one or more rapidly rotating rolls, either 55 smooth or peripheral grooves or projections

which dip in the body of tar or pitch in the bottom of the apparatus and cause a continuous intense spray of the tar or pitch to fill all parts of the apparatus so that the entering high temperature steam is immediately 55 cooled by contact with the intense spray with resulting rapid heating and vaporization of oil constituents from the spray. Steam which is superheated to temperatures around 600 to 1000° C. can thus be supplied in regulated 60 amount to a still having one or more rapidly rotating spray rolls and continuously supplied with tar or pitch to be distilled and the rate of supply of the steam and of the tar or pitch can be so regulated that rapid 65 and continuous distillation can be accom- 70 plished and pitch of high melting point produced, e. g. pitch up to around 400° F. melt- 75 ing point or higher, with an unusually high yield of oil from the tar amounting to around 75% or higher, and varying somewhat with the character of the tar distilled. The rapid- 80 ity with which the highly superheated steam is cooled to a temperature below that at which objectionable decomposition of the pitch 85 takes place is such that the decomposition can be reduced to a minimum and rapid and effective distillation nevertheless accom- 90 plished. Where some decomposition is de- 95 sired, in order, for example, to increase the carbon content of the pitch residue, this can readily be accomplished by regulation of the temperature, the rate of supply of the steam and of the pitch spray in the chamber or by prolonging the time of contact of the pitch 95 in the chamber with the hot steam.

In carrying out the process, the intensity of contact of the pitch and steam will ordi- 100 narily be such that the steam can pass through the chamber at a rapid rate so that it is in contact with the intense spray of tar or pitch only for a short period of time, amounting for example, to from one to five seconds, more or less, depending upon the size of the apparatus and the conditions of operation. Similarly, the supply of tar or partly distilled tar to the still, and the removal of high melting point pitch there- 105 from, can be so regulated that the entire period of operation from the time the tar en-

- ters until the pitch leaves will be short, amounting, for example, to as little as one minute or less in some cases or to five or ten minutes or more in other cases. Only a very short time is required, with the intense atomizing and spraying of the pitch into the hot steam, and with a regulated supply of the highly superheated steam, to accomplish distillation of the tar to the desired extent.
- 10 The tar which is distilled may be ordinary coal tar from coke oven or gas retort plants or it may be other tars such as low temperature tars, water gas tars, producer gas tars, etc. Instead of distilling total tars, heavier or lighter tar fractions can be distilled, such as the heavier tar recovered from the collector main of a by-product recovery plant or the lighter tar recovered from the condensers of such a plant.
- 15 The distillation can be carried to the extent necessary to produce a pitch of higher or lower melting point, as desired, and a greater or less percentage of distillate oils, but it is one advantage of the present process that it enables an unusually high yield of distillate oils to be produced, and an unusually high melting point pitch to be produced, rapidly, and continuously, and with relatively little decomposition of the pitch produced.
- 20 In some cases, pitches of intermediate melting point may be desired, e. g. around 150° or 200° or 250° F. melting point; while in other cases higher melting point pitches may be desired, up to 300° F. melting point or even up to 400° F. melting point or higher. These pitches can readily be produced according to the present process.
- 25 The superheated steam which is employed in the present process need not be under a high pressure, although, where high pressure steam is available, it can be employed. Low pressure exhaust steam which is available at many plants can readily be superheated to a high temperature and employed in the present process. The superheaters may be of suitable construction to enable the steam to be superheated to the desired high temperature. A pipe coil superheater can be employed located adjacent the still so as to supply superheated steam in a continuous manner directly to the still.
- 30 The still itself may vary in its construction but it should have provision for forming an intense spray of the tar or pitch to be distilled so that the highly superheated steam will be almost instantly cooled to a temperature below that at which objectionable carbonization and coking will result. The forming of such an intense spray with a rapidly rotating roll will not only effect rapid cooling of the steam and utilization of its heat for distillation, but will keep the interior of the still washed with the pitch spray and thereby prevent the interior walls from being coated with coke. The tar is advan-

tageously supplied to the still in a continuous manner, and the pitch produced continuously withdrawn.

In distilling tar to produce a pitch of high melting point, e. g. around 400° F. or higher, the steam and admixed oil vapors will leave the still at a high temperature, for example, around 300° C. or higher, although the temperature may be somewhat lower and may vary with the method of operation, the character or melting point of pitch produced, etc. Steam and oil vapors at such high temperature carry a large amount of heat which can advantageously be employed for preheating and distilling tar, and such preheating and distillation can be combined with the distillation proper so that the partly distilled tar is supplied to the still proper for further distillation. The preheating of the tar by the hot steam and vapors will result in cooling the steam and vapors and condensing some of the higher boiling oil constituents therefrom. By carrying out the condensation in a countercurrent manner, a large part of the heat contained in the steam and vapors can be recovered for use in preheating and distilling tar at the same time that the oil vapors are themselves condensed.

It is one advantage of the present invention that the use of the highly superheated steam enables a radically smaller amount of steam to be employed for accomplishing the distillation so that the oil vapors distilled are admixed with a relatively small amount of steam, as compared with processes heretofore proposed. As a result, the oil vapors can more readily be condensed from the steam, and, if the steam is itself condensed, there will be much less steam to be condensed.

For example, using superheated steam superheated to a temperature of about 600° C. and supplying to the still dehydrated tar which is preheated to a temperature around 150° C., it is possible to distill about 115 gallons of tar to produce pitch of around 400° F. melting point per 1000 pounds of superheated steam supplied, with a resulting temperature of the steam and vapors leaving the still of about 285° C. If the hot steam and vapors leaving the still are employed for preheating and partly distilling the tar, a radically increased rate of distillation can be accomplished with the same amount of steam.

Instead of condensing the steam it may be freed from admixed oil vapors as much as possible and then recirculated and reheated for use over again in the process. If the tar is preheated and the lower boiling oil constituents are distilled therefrom before the resulting pitch is brought into direct contact with the highly superheated steam in the still, the distillate produced by the steam distillation will be made up of higher boiling oil constituents which are readily condensable.

from the steam at a temperature above that at which the steam itself condenses. Operating in this way, there will be but little if any oil vapors left admixed with the steam at a temperature approaching that of condensation, and the steam freed as much as possible from oil vapors can then be recirculated through the superheater and used over again in the process. Where exhaust steam is available or the expense of the steam is not an item of importance, fresh steam can be employed without recirculation and the steam condensed with the last oil fractions.

The invention will be further described in connection with the accompanying drawings, which illustrate in a somewhat conventional and diagrammatic manner, an arrangement of apparatus for carrying out the invention, but it is intended and will be understood that the invention is not limited thereto.

Referring to the apparatus shown somewhat diagrammatically and conventionally in the accompanying drawing, the steam superheater is shown as a pipe coil superheater 1 suitably arranged in a heating furnace 2 and discharging through the pipe 3 to the still 4. The still has within it a cylindrical roll 5 adapted to be rotated by a directly connected electrical motor 6 so that the rotation may be at a rapid rate e. g. 900-1100 R. P. M. Located above the opposite end of the still is the settling chamber 7 through which the steam and vapors escape and in which removal of entrained tar or pitch constituents takes place. A cap 36 of any well-known type may be provided above the gas and vapor exit from the still to distribute the gas and vapors about the base of settling chamber 7 and to prevent the introduction of tar into the still through the gas and vapor exit. The steam and vapors pass through the line 8 to the first of a series of fractional condensers and indirect heat interchangers and pre-heaters 9, 11 and 13. From the first condenser or heat interchanger the steam and uncondensed vapors pass through the line 10 to the second heat interchanger 11, thence through the line 12 to the third heat interchanger 13, and any remaining uncondensed vapors and steam escape through the line 14 to an exhauster by means of which the flow of steam through the system can be regulated.

Tar is supplied through the line 16 to the space surrounding the tubes of the heat interchanger 13 and is there preheated, any resulting vapors escaping through the line 17 to the condenser 18 and being there condensed. The preheated tar then flows through the line 19 to the space 20 of the second heat interchanger 11 where it is further heated, the resulting vapors escaping through the line 21 to the condenser 22 and being there condensed and the undistilled tar residue escaping through the line 23 to

the heat interchanger 9 where it is further heated and distilled in the space 24, the resulting vapors escaping through the line 25 to the condenser 26 and being there condensed and the pitch residue escaping through the line 27 to the distributing device 28 located in the settling chamber 7. The pitch flows down over the baffles 29 in the chamber 7 and then through the line 30 the end of the still at which the superheated steam enters. The pitch residue is withdrawn from the still through the line 31. The condensate formed in the indirect condensers 9, 11 and 13 is drawn off at 32, 33 and 34 respectively as oil fractions of progressively decreasing boiling point range. The apparatus illustrated provides for a plurality of fractions partly from the preheating and partial distillation of the tar and partly from the further distillation which takes place in the still proper. With such an arrangement, the lower boiling oil constituents can be removed from the tar in a concentrated state, that is, without coming in contact with the superheated steam, and only the partially distilled tar or pitch then subjected to further distillation by direct contact with the highly superheated steam. The oil vapors distilled by the steam will therefore be for the most part high boiling oil vapors which can readily be condensed from the steam for the most part or entirely without cooling the steam to its temperature of condensation, although the steam may also be condensed in the last condenser where it is not to be used over again, and its latent heat of condensation can thereby be made available to aid in pre-heating cold tar.

In the apparatus illustrated, the general flow of the tar or pitch and steam in the still, is a concurrent flow so that the highly superheated steam entering the still first comes in contact with the pitch of lowest melting point containing the largest proportion of oil constituents. The rapid distillation of such oil constituents from the tar or pitch rapidly cools the steam to a temperature below that at which objectionable decomposition of the pitch will take place. The pitch of highest melting point will escape from the outlet end of the still and will be approximately in equilibrium with the escaping steam and vapors. Accordingly, even though the steam may be at a high temperature of superheat, far in excess of that to which tar or pitch can be heated without coking, the intensity of the spray of tar or pitch is so great that the steam is almost instantly cooled to a temperature below that at which such objectionable coking will take place with correspondingly rapid utilization of the heat of the steam for distilling the tar or pitch. Even with steam at somewhat lower temperatures than those mentioned, the superheat of the steam can be utilized in a particu-

larly advantageous manner in a still of the type above described.

I claim:

1. The improvement in the distillation of tar and the production of pitch with superheated steam, which comprises superheating the steam to a temperature at which it will rapidly coke the tar if brought into prolonged contact therewith, bringing the resulting superheated steam into direct and intimate contact with a spray of tar of such intensity that the steam is almost instantly cooled to a temperature below that of objectionable coking of the tar, thereby effecting correspondingly rapid distillation of the tar to pitch, and withdrawing the resulting steam and oil vapors and cooling the same to condense the oils therefrom.
2. The improvement in the distillation of tar and the production of pitch with superheated steam, which comprises superheating the steam to a temperature in excess of 500° C., bringing the superheated steam continuously into a still containing a body of the tar to be distilled, spraying the tar into the steam in the form of an intense spray which will almost instantly cool the highly superheated steam to a temperature approximating that of the spray and correspondingly heat the spray to a temperature approximating that to which the steam is cooled, withdrawing the resulting pitch residue from the still and supplying additional tar to be distilled in a continuous manner and continuously withdrawing the resulting steam and oil vapors and cooling the same to condense the oil constituents therefrom.
3. The improvement in the distillation of tar and the production of pitch with superheated steam, which comprises superheating the steam to a temperature in excess of 600° C., bringing the superheated steam continuously into a still containing a body of the tar to be distilled, spraying the tar into the steam in the form of an intense spray which will almost instantly cool the highly superheated steam to a temperature approximating that of the spray and correspondingly heat the spray to a temperature approximating that to which the steam is cooled, withdrawing the resulting pitch residue from the still and supplying additional tar to be distilled in a continuous manner and continuously withdrawing the resulting steam and oil vapors and cooling the same to condense the oil constituents therefrom.
4. The method of distilling tar and the production of pitch and of producing pitch of a melting point around 350 to 400° F. or higher and a high yield of distillate oils, which comprises superheating steam to a temperature at which it will rapidly coke the tar if brought into prolonged contact therewith, continuously supplying the superheated steam to a still, continuously subject-

ing the steam to an intense spray of tar to be distilled of such intensity that the steam is almost instantly cooled to a temperature below that of objectionable coking and the tar is rapidly distilled, regulating the supply of tar to be distilled so that pitch of a desired high melting point is produced and withdrawing the same continuously, and withdrawing the steam and oil vapors from the still and cooling the same to condense the oils.

5. The improvement in the distillation of tar and the production of pitch with superheated steam, which comprises superheating the steam to a temperature at which it will rapidly coke the tar if brought into prolonged contact therewith, supplying the superheated steam continuously to a still, supplying partly distilled and preheated tar to the still and spraying the same into the steam with such intensity that the steam is almost instantly cooled to a temperature below that of objectionable coking and the tar is rapidly distilled to produce a high melting point pitch, withdrawing the steam and resulting vapors from the still and passing them into indirect heat interchanging relation with tar to preheat the tar and partially distill the same, and supplying the resulting partially distilled and preheated tar to the still for further distillation by direct contact with the superheated steam.

6. The improvement in the distillation of tar with steam superheated to a temperature between 600 and 1000° C., which comprises passing the superheated steam through a still while spraying the tar into the steam in the form of a spray so fine and intense that the tar rapidly distills to pitch by the self-contained heat of the steam and the steam is rapidly cooled to a temperature approximating that of the spray while continuously adding tar to the still and withdrawing pitch residue therefrom.

7. Apparatus for distilling tar to produce pitch, comprising, in combination, a tar still, means in the still to produce an intense spray of tar therein, a superheater for heating gas, means for passing said superheated gas from the superheater through the intense spray of tar in the still and thus distill the tar to pitch, and a condenser connected with said tar still for condensing the vapor coming off therefrom.

8. Apparatus for distilling tar to produce pitch, comprising, in combination, a tar still, means in the still to produce an intense spray of tar therein, a superheater for heating gas, means for passing said superheated gas from the superheater through the intense spray of tar in the still and thus distill the tar to pitch, a heat interchanger connected with said tar still for receiving the vapor and hot gas from the still and for passing tar in heat interchange relationship with said vapor

and hot gas to said still, thus preheating the tar introduced into said still.

9. Apparatus for distilling tar to produce pitch, comprising, in combination, a tar still, means in the still to produce an intense spray of tar therein, a steam superheater, means for passing superheated steam from the superheater through the intense spray of tar in the still and thus distill the tar to pitch, a series of heat interchangers communicating with said tar still for receiving the steam and volatiles removed from the tar from the still and condensing the volatiles, said interchangers functioning to pass tar to the still in heat interchange relationship with said steam and volatiles and thus preheat the tar introduced into the still.
